UNITED STATES PATENT OFFICE.

JOHN HICKS, OF CALGARY, ALBERTA, CANADA.

GAS-BURNER.

1,102,751.

Specification of Letters Patent. Patented July 7, 1914.

Application filed March 21, 1914. Serial No. 826,188.

To all whom it may concern:

Be it known that I, JOHN HICKS, a subject of the King of Great Britain, and a resident of the city of Calgary, in the Province of Alberta, Canada, have invented certain new and useful Improvements in Gas-Burners, of which the following is the specification.

My invention relates to improvements in 10 gas burners and the object of the invention is to devise a burner particularly adaptable to gas furnaces and which will produce a greater and cheaper heat than that which has heretofore been obtained by other fuels 15 and by which the gas and air are thoroughly mixed to form a combustible mixture and it consists essentially of a tapered tube open at the ends, a valve casing secured to the lower end of the tube and having an open 20 bottom, a controlling valve for such open bottom, a gas supply pipe entering the casing and having an up-turned portion located in the center of the tube, a controlling valve for such inlet pipe and a perforated covering cap 25 detachably secured over the open end of the up-turned portion as hereinafter more particularly explained by the following specification.

Figure 1, is a sectional view of my device. 30 Fig. 2, is a sectional plan.

In the drawings like letters of reference indicate corresponding parts in each figure.

A is the bottom of the furnace fire pot provided with an internally threaded opening 35 A'.

B is a tapered tube provided with an externally threaded upper end designed to be threaded into the opening A'. The lower end of the tube B is preferably enlarged at 40 B' as shown, such enlarged portion terminating in an externally threaded portion B².

C is the valve casing provided with an internally threaded orifice C' into which the externally threaded end of the tube B² is 45 screwed.

C² is an opening formed in the valve casing directly opposite the open upper end of the tube B.

C' is an internally threaded opening 50 formed in the side of the valve casing.

D is the gas supply tube.

D' is a controlling valve designed to control the supply of gas passing through the tube.

The pipe D is connected by a suitable 55 union D² which is threaded into the internally threaded opening C² of the valve casing thereby connecting the pipe D to the valve casing.

D⁴ is an upwardly extending elbow into 60 which the pipe D leads through the union piece D². The elbow D⁴ extends upwardly and centrally into the lower end of the tube B.

D⁵ is a perforated cap which is threaded 65 on to the upper end of the elbow D⁴.

E is a swinging valve disk extending over the open lower end of the valve casing C' to which it is pivotally connected by a set screw E'.

It will thus be seen that when it is desired to use my burner the valve D' is 70 opened, the gas passing through such valve into the elbow D⁴ up through the perforated cap and into the tube B. The disk valve E 75 is swung laterally so as to admit air through the open end C² of the valve casing. The upward rush of gas through the tube B draws the air through the opening C² so as to mix with the upgoing stream of gas and 80 thereby form a perfect combustible mixture.

When desired the cap D⁵ may be changed for another cap having different sized perforations, so as to make the burner adaptable to the gas pressure existing in the gas 85 supply pipe. The valve E may also be adjusted for the same purpose.

From this description it will be seen that I have devised a very simple device for 90 burning gas in heating furnaces which will be cheap, economical and provide a thorough combustible mixture.

What I claim as my invention is:

1. A gas burner comprising a vertical tube, a valve casing secured to the lower end 95 of the tube and having an opening opposite the open lower end of the tube, a disk valve extending normally over such opening, a set screw pivotally securing such disk at one side of the opening, and a gas supply pipe 100 entering through the side of the valve casing and terminating in an up-turned portion extending into the center of the aforesaid tube, as and for the purpose specified.

2. A gas burner comprising a vertical 105 tube, a valve casing secured to the lower end of the tube and having an opening opposite the open lower end of the tube, a disk valve

extending normally over such opening, a set screw pivotally securing such disk at one side of the opening, a gas supply pipe entering through the side of the valve casing and terminating in an up-turned portion extending into the center of the aforesaid tube, and a perforated cap extending over the

open end of such up-turned portion, as and for the purpose specified.

JOHN HICKS.
